UNITED STATES PATENT OFFICE

JOHN EDWARD HICKEY, OF FALL RIVER, MASSACHUSETTS

TRACK ALIGNING MACHINE

Application filed March 25, 1931. Serial No. 525,266.

The present invention relates to new and useful improvements in machines for operating upon railway tracks, and more particularly it pertains to a machine for use in 5 aligning the rails of a railway track.

It is one of the objects of the invention, to provide a machine which will replace or supplant the ordinary track aligning bar, and which will eliminate the laborious operation attendant the use of said aligning bar.

It is a further object of the invention so to construct a machine of the aforementioned character that it may be effectively operated 15 by a comparatively small number of men.

It is a still further object of the invention to provide a machine of the aforementioned character which is readily portable from place to place, and which may be quickly 20 and easily removed from its operative position upon a section of railway track upon which it is operated.

It is a still further object of the invention to provide a machine of this character which 25 will in no wise damage the rail upon which it is operating during the process of aligning the track.

It is a still further object of the invention so to construct a machine of the aforementioned character to successfully operate the ballasts or perform other operations necessary to the successful operation of an aligning bar, and thus facilitate the aligning operation.

35 It is still a further object of the invention so to construct a machine of this character that the section of the rail being operated upon will not be obscured and may be sighted by the person or persons performing the operation.

It is a still further object of the invention so to construct the machine that in its movement over a section of track to be operated upon, the supporting wheels of the machine will follow the rails of the track

even though said rails may be out of alignment.

Other objects of the invention will appear as the nature of the invention is better understood, and for this purpose reference will be had to the accompanying drawings, wherein;

Figure 1 is a top plan view illustrating diagrammatically a section of railway roadbed, illustrating a machine constructed in accordance with the present invention in place upon the rails of the roadbed,

Figure 2 is a view illustrating the machine in end elevation,

Figure 3 is a view illustrating the machine in side elevation,

Figure 4 is a detail sectional view illustrating the manner in which the supporting wheels of the machine are mounted,

Figure 5 is a detail elevational view showing a portion of the machine,

Figure 6 is a view illustrating the manner in which the machine may be removed from the rails of a railway roadbed, and;

Figure 7 is a detail perspective view illustrating one of a plurality of detachable wheels adapted to be removably secured to the machine for the purpose of removing it from the railway roadbed in a lateral direction.

Referring specifically to the drawings, the ballast of the roadbed is designated B, and the rails of the roadbed are designated A, the cross ties being designated C. The rails A are secured in position upon the cross ties 30 C by spikes or the like D, or in any other conventional manner.

A machine for aligning the rails A and which is constructed in accordance with the present invention, is designated generally in 35 the drawings by the reference character E and this machine includes side frames 10 which have an offset portion 11 the purpose of which will be hereinafter more specifically described. The side frames 10 are supported 40

by axles or the like 12 which extend through the side frames, at the ends thereof and upon which supporting wheels such as 13 are mounted. These supporting wheels have relatively narrow flanges and are flanged as indicated at 14 in Figure 4 and have a tread portion 15 which is adapted for engagement with the tread portion of the ball of the rails A. By reference to Figure 4 it will be noted that these supporting wheels 14 are loosely mounted upon the axles 12 and have both rotary and sliding movement on said axles. The wheels 14 are forced longitudinally of the axles in one direction by means of a coil spring or the like 16 which is mounted between its respective wheel 13 and the point where its respective axle passes through the side frames 11 of the machine and movement of the wheels toward the free end of the axles 12 is prevented by means of a nut or the like 17 which nuts are threaded upon the free ends of the axles 12.

Thus it will be apparent that the several springs 16 function to maintain the flange of their respective wheels in engagement with the rails upon which the wheels are travelling, and that this construction operates to cause the wheels to follow the rails at all times.

Supporting bars such as 20 extend transversely of the machine, and in the present illustration of the invention three of these bars are shown. Movable upon the bars, there is a weight or the like 21 and the bars 20 pass through openings in the weight 21 and thereby provide means for supporting the weight. The weight is adapted for movement longitudinally of the bars 20 or transversely of the machine, and for the purpose of moving the weight 21, it is provided with adjustable handles such as designated 22 in the drawings.

Means is provided to receive the impact of the blow of the weight 21 and transmit said impact to the rail, and in the present embodiment of the invention, this means consists of plates 30 slidably mounted upon the bars 20. These plates are cut away as at 31 throughout their upper portion, and are provided with a projection 32 which when the plates 30 are in operative position, engage the side of the ball of the rail as best illustrated in Figure 2.

By this construction it will be apparent that as the weight is moved upon the rods or bars 20, the impact of the blow incident to the weight contacting with the plates 30 will be transmitted through the plates 30 to the rails, and will cause the entire track structure to be moved, and this operation is to be repeated from time to time until the proper alignment of the track structure being operated upon is obtained.

As best illustrated in Figures 1 and 3, the side frames are provided with pockets or the

like 35, and these pockets are preferably rectangular in shape. In Figure 7 there is shown a supporting wheel of the caster type which consists of a wheel member 36 mounted within a suitable yoke 37 having a curved upwardly extending stem 38 which in turn has a squared end 39 for engagement in the pocket 35 in order that the wheels 36 may be mounted on one side or the other of the machine as illustrated in Figure 6.

The wheels 36 just mentioned are employed to support the machine when the same is not in position upon the rails of the roadbed, and also for removing the machine from the rails when it is in position thereon.

In operation of the machine, the weight 21 is moved from side to side thereof in order to impart its force in the desired direction it being understood that this force is transmitted to the rails through the plates 30 as heretofore described.

When it is desired to move the machine along the track from one location to another, the weight 21 and the plates 30 are moved to elevated position, and to accomplish this, the rods or bars 20 heretofore mentioned are moved upwardly and positioned in recesses 45 in the upper edge of the side frames of the machine which recesses are best illustrated in Figure 3 and this will support both the weight and the plates 30 above the rail and will permit of clearance of these elements when the device is being moved from place to place and encounters a switch cross over or the like. When it is desired to use the device again, the rods are lowered to the position in which they are shown in the drawings and the several parts are in the proper position for operation upon a rail. The raising and lowering of the parts may be accomplished by moving the weight 21 to one end of the rods 20 after which the opposite end of the rods to that upon which the weight is carried are lowered or raised as the case may be into the desired position after which the weight is moved to the opposite ends of the rods 20 and those ends from which the weight was just removed are manipulated in a similar manner.

When it is desired to remove the machine from a roadway, the weight 21 is shifted to one side of the machine, and the opposite side of the machine is lifted and the wheels 36 inserted into their sockets as heretofore described after which the weight is then moved to the opposite side of the machine and that side from which the weight was moved last is elevated and after which the device may be rolled from position upon the roadbed, or it may be turned directly over end for end in case it is necessary to hurriedly remove the machine from the track roadway.

While the invention has been herein illustrated in what may be termed a preferred form, it is to be understood that the invention is not to be limited to the specific con-

struction herein shown, but that it may be carried out in other forms without departing from the spirit thereof.

Having thus described the invention, what is claimed as new, and what is desired to secure by Letters Patent of the United States, is:

1. A track aligning machine comprising means movable over the track to be aligned, track engaging means carried thereby, and means for subjecting said track engaging means to one or more intermittent sudden blows, the impact of which is transmitted to the track.

15 2. A track aligning machine comprising means movable over the track to be aligned, track engaging means carried thereby, and a slidably mounted weight adapted to be moved intermittently into engagement with said 20 track engaging means.

25 3. A track aligning machine comprising means movable over the track to be aligned, means for subjecting said track to one or more intermittent sudden blows, and means interposed between said last mentioned means and the track for transmitting the force of the blows to the track.

4. A track aligning machine comprising a car, means for supporting said car upon the 30 track to be aligned, track engaging means carried by said car and adjustable into engagement with the track to be aligned and impact producing means movable transversely of the track to be aligned, and into engagement with said track engaging means.

5. A track aligning machine comprising a car movable over a track to be aligned, said car including rotating, and slidably mounted wheels, impact producing means carried by 40 the car, means for transmitting the impact of said impact producing means to the track to be aligned, and means having engagement with said slidably mounted wheels to cause the wheels to follow changes in the track to be 45 aligned simultaneously with the aligning operation.

6. A track aligning machine comprising a car for support and movement upon the track to be aligned, a plurality of supporting rods 50 extending transversely of said car, track engaging means carried by said supporting rods, and means carried by said supporting rods and movable intermittently into engagement with the track engaging means.

55 7. A track aligning machine comprising a car for support and movement upon the track to be aligned, side frames for the car, transversely extending rods supported from said side frames, track engaging means carried by 60 said rods, means carried by said supporting rods for imparting intermittent blows to said track engaging means, and means whereby the track engaging means may be supported out of track engaging position.

65 8. A track aligning machine comprising a

car for support and movement upon the track to be aligned, side frames for the car, transversely extending rods supported from said side frames, track engaging means carried by said rods, means carried by said supporting rods for imparting intermittent blows to said track engaging means, and means whereby the track engaging means may be supported out of track engaging position, said last mentioned means comprising a plurality of 70 shoulders at different heights in the side frames for supporting said transversely extending rods.

In testimony whereof I affix my signature.
